M. H. HANSEN

CYLINDER REBORING MACHINE

Filed Aug. 8, 1921

Patented July 17, 1923.

1,461,877

UNITED STATES PATENT OFFICE.

MAURICE H. HANSEN, OF SEATTLE, WASHINGTON.

CYLINDER-REBORING MACHINE.

Application filed August 6, 1921. Serial No. 490,630.

To all whom it may concern:

Be it known that I, MAURICE H. HANSEN, a citizen of the United States, and a resident of the city of Seattle, county of King, State of Washington, have invented certain new and useful Improvements in Cylinder-Reboring Machines, of which the following is a specification.

This invention relates to improvements in cylinder reboring machines and more particularly to machines of that character for reboring the worn cylinders in automobile engines, or the like.

Due to the character of the reboring machines now commonly in use, it has been necessary here-to-fore, when it was desired to rebore the cylinders of an automobile engine, to first remove the engine from the vehicle and take it to the boring machine. This method of operation not only requires considerable time and labor in removing and positioning the engine within the boring machine, but also is expensive.

It is, therefore, the object of this invention to overcome the above disadvantages by the provision of a portable, motor driven machine that may be mounted upon the cylinders of an engine, after the head has been removed therefrom, and may be secured thereon in proper position for reboring the cylinders, without the necessity of the engine first being removed from the vehicle chassis.

Other objects of the invention reside in the details of construction of a base plate for supporting the boring mechanism which permits the device to be mounted upon the cylinders, and in the means for securing the same to the engine during operation.

Other objects of the invention reside in the details of construction of the means for driving the boring device and for automatically advancing the cutter while it is being driven.

In accomplishing these and other objects, I have provided the improved details of construction, the preferred forms of which are illustrated in the accompanying drawings, wherein—

Figure 1 is a side elevation of a boring device, constructed according to the present invention, mounted functionally in position for reboring the cylinder of an automobile engine; part of the engine being broken away to show the manner of securing the device thereto.

Figure 2 is an enlarged, longitudinal, sectional view of the reboring machine.

Figure 3 is a horizontal section taken on the line 3—3 in Figure 2.

Figure 4 is a horizontal section on the line 4—4 in Figure 2, illustrating the means for locking the cutter advancing rod against rotation.

Referring more in detail to the drawings—

1 designates a bed plate whereon the operating parts of the machine are mounted and which is adapted to seat upon the upper ends of the cylinders 2 of an engine, 70 after the head has been removed therefrom, as is illustrated in Figure 1 of the drawings. This plate 1 is provided centrally with a longitudinally directed slot 3 through which a bolt 4 is extended. At its lower end, the bolt is fixed to a cross bar 5, that is adapted to extend across and engage the lower end of the cylinder adjacent the one being rebored, and, at its upper end, is threaded and has a nut 6 thereon which may be tightened against the plate to secure the machine in position upon the engine.

At one end of the plate 1 is a vertical standard 7, provided on its outer face with vertically aligned, spaced apart bearings 8 and 9 wherein is contained a revolubly mounted and longitudinally movable boring shaft 10. This shaft is rotatably driven by means of an electric motor 11 fixedly mounted upon the bed plate and which is connected for driving the shaft through a series of gears, consisting of a worm gear 12 that is slidably keyed to the shaft 10 between the bearings 8 and 9, a pinion 13 that is fixed on the motor shaft 14, a worm 15 and driving gear 16 that are fixed on the opposite ends of a shaft 17 that is rotatably mounted in a bearing 18 on one side of the standard 7. The worm 15 and gear 16 respectively mesh with the worm gear 12 and pinion 13, and the proportions of the several gears are such that the connection provides for a substantial reduction of speed between the motor and boring shaft. 100

Threaded into the upper end of the bearing 8, in such manner that it will slidably contain the upper end of the boring shaft 10 for rotatable and longitudinal movement therein, is a tube 20. This is closed by a wall at its upper end which has a threaded rod 21 extending therethrough and slidable

within a hole 22 bored longitudinally and centrally within the upper end of the boring shaft. Within the upper end of the tube 20, a bearing collar 25 is fixed on the rod 21 and on the outside of the tube, a nut 26 is fixed against rotation on the rod, and, interposed between the collar and nut and against opposite sides of the end wall of the tube, are thrust bearings 27-27'; the construction being such that the rod 21 will be held against longitudinal movement but may be rotated within the sleeve and within the bore of the shaft 10.

Fixed within the upper end of the boring shaft by means of set screws 29, is a sleeve or collar 30 through which the rod 21 is threaded, and fixed on the outside and adjacent the upper end of the tube 20, is a bracket 32 having a forked arm 33 pivotally fixed therein in position that it may be moved to engage the nut 26 to thereby prevent rotation of the shaft 21.

It is apparent that should the rod 21 be held against rotation, while the boring shaft 10 is being driven, the latter will be caused to move outwardly, due to the threaded connection between the rod 21 and the sleeve 30.

At the lower end of the boring shaft 10 is a cutter head 40 which may be of any desired type suitable for the reboring of cylinders, preferably of an expandable type, and at the outer end of the rod 21 is a crank for turning the rod to manually adjust or withdraw the cutter from a cylinder.

Assuming that the device is so constructed in using the same to rebore a cylinder of an engine, the head is first removed from the engine and the machine mounted upon the upper ends of the cylinders and secured thereto by means of the bolt 4 as shown in Fig. 1. The cutter head is then adjusted to the desired position within the cylinder by rotating the shaft 21 by means of the handle fixed on the upper end thereof. After proper adjustment of the cutter has been made, the locking arm 33 is moved to enclose the nut 26 so that the rod 21 will be held against rotation thereby. Operation of the motor 11 will then rotate the boring shaft and cutter head, and the shaft will be advanced downwardly within the cylinder as it rotates by means of the threaded connection of the sleeve 30 secured therein with the rod 21.

It will be noted that such a device could be mounted upon the engine without necessitating the removal of the engine from the vehicle and that the cost of reboring cylinders, as compared to the cost of using the present type of machines, would be very small.

It is further apparent that various means could be used to drive the boring shaft other than the one here shown, and without departing from the spirit of the invention, and for this reason, I do not wish to be limited only to the details of construction shown.

Having thus described my invention, what I claim as new therein and desire to secure by Letters-Patent, is:

1. A cylinder reboring machine comprising a base plate applicable at the ends of the cylinders of an engine and adapted to be adjustably anchored thereto, a standard at one end of the plate having bearings formed thereon, a boring shaft rotatably and longitudinally movable in said bearings, a boring tool fixed to the lower end of the shaft, a sleeve fixed in the upper of said bearings and slidably containing the upper end of the boring shaft, an adjusting rod rotatably fixed in said sleeve and extended in a threaded connection concentrically within the boring shaft, means for manually rotating the adjusting rod to effect longitudinal adjustment of the boring shaft, and means for holding the adjusting rod against rotation to effect automatic advancement of the boring shaft when in operation.

2. A cylinder reboring machine comprising a base plate, a standard on the plate having vertically aligned bearings thereon, a boring shaft rotatably and longitudinally movable in said bearings, a reboring tool fixed upon the lower end of said shaft, a sleeve fixed at its lower end in the upper of said bearings and slidably containing the upper end of the boring shaft, an advancing shaft rotatably fixed in said sleeve with its lower end threaded co-axially into the boring shaft, a crank fixed to the outer end of the advancing shaft, and a pivotally movable locking arm fixed on the sleeve and movable into and from holding relation with the locking head.

Signed at Seattle, Washington, this 2nd day of August 1921.

MAURICE H. HANSEN.
